UNITED STATES PATENT OFFICE

CECIL J. NOCK, OF BROOKLYN, AND JORDAN DJAZOS, OF NEW YORK, N. Y.

WINDOW ANTIRATTLE AND LOCK DEVICE

Application filed October 2, 1928. Serial No. 309,773.

This invention relates to window anti-rattler and latching devices, and in particular to one which may be placed on the window and which can be thrown back out of the way 5 when not in use.

The particular object of the invention is to provide an anti-rattling device which will at the same time serve as a latching means whereby intrusion through the window is prevented, this device being so arranged that it may be placed on the sash frame and extended to a position to engage both sashes simultaneously to prevent rattling thereof at the same time serving with the aid of a member on one of the sashes to prevent unauthorized admission through the window.

A still further object of the invention is to provide a device which is adjustable, so that the take-up of the space between the sashes is possible and therefore rattling prevented, the device being made of few parts and being readily punched from metal, so that the cost may be kept at a minimum.

To enable others skilled in the art to fully comprehend the underlying features of my invention that they may embody the same in the various modifications in construction and relation contemplated, a drawing depicting a preferred form has been annexed as a part of this disclosure, and in such drawing similar reference characters denote corresponding parts throughout all the views, of which,

Figure 1 is a fragmentary view in elevation of an upper and lower sash and adjacent sash frame, the latter having secured thereto my improved window anti-rattler and locking device,

Figure 2 is a top plan view of the sashes and sash frame, illustrated in Figure 1, the latching and anti-rattling device being clearly illustrated in the position which it will assume when serving both as a lock and anti-rattler, and,

Figure 3 is a view in perspective of my anti-rattler and latch fastener.

Referring to the drawing in detail, 5 indicates the sash frame of a window construction, upon which are mounted the parting strips which define guide ways 7 in which the lower and upper sashes 8 and 9 respec-

tively slide. As is well known the placing of these parting strips 6 is not always done accurately by the carpenter, with the result that the sashes 8 and 9 have considerable play, and on a windy day rattling of the sashes 55 results, which not only is annoying but has a tendency to loosen the window pane and sometimes break the same.

In carrying out my invention, one of the objects is to provide an antirattling device and to this end I have made use of a base plate 10 having suitable openings 11 therein for the reception of the screws 12 through the medium of which said base plate 10 may be secured to the sash frame 5 at a point suitable 60 for the latch arm, so that the same will be in position to just bring over the upper edge of the lower sash. This base plate 10 is provided with suitable knuckle 13, through which is passed a hinge pin 14 the ends of which are 65 headed and which is arranged to also pass through an ear 15 formed on the hinged end of a latch arm 16. This latch arm is of course 70 arranged to swing about the hinge pin 14, and its end is arranged to be positioned directly over the upper edge of the lower sash, 75 its extreme end being positioned within the pane carrying portion of the upper sash.

This latch arm 16 is provided with suitable shoulders 17 on its opposite edges, which 80 mark the termination of a widened portion 18 of said arm, the extended portion of the arm being reduced as at 19 and 20, the portion 19 being arranged to fit in the opening 21 of the upper sash which carries the window pane. 85 At the side edge of this opening 21 and positioned sufficiently high on the sash to permit passage of the end 19 of the latch arm 16 thereunder, I provide an L-shaped 90 angle member 22 the horizontal 23 of which, as will be noted in Figures 1 and 2, being arranged to overlie the end of the portion 19 and the portion 20 of the latch arm when the upper sash has been completely closed and when the lower sash has been lowered to permit swinging of said arm 16 into position under said angle plate. At the time that the arm 16 is swung to the position just described the shoulder 17 of the under edge thereof 95 will come into engagement with the top outer 100 corner of the angle member 22.

base of the lower sash 8, thus jamming it against the middle parting strip 6, and it will be quite evident that the end of the arm 16 in its portion 20 is against the sash 9 beneath the angle member 22, therefore holding or jamming said sash 9 against its parting strip 6, so that not only are the sashes locked relatively to each other but they are also prevented from rattling.

10 The latch arm 16 is cut on both sides identically the same manner, so that it can serve at the left side of the sash frame or at the right side whichever is most convenient to the user.

15 In order that the arm 16 may be locked in its antirattling and sash latching position, I have provided in the widened portion 18 of the arm 16 an elongated slot 24 in which is positioned the reduced part of a shank 25 of

20 a lock screw 26, the threaded end 27 of which is arranged to enter an angularly disposed threaded opening in the base plate 10. It is of course quite evident that by the operation of this screw 26 the plate 16 may be advanced or 25 retracted away from the sashes, and can be very forcibly urged in contact therewith by the screwing in of the threaded member 26.

It is evident therefore that we have provided a new and improved window anti-rattler and 30 locking device, which may be secured to the sash of a window construction adjacent the upper and lower sashes and which may be arranged to swing into operating position or may be swung out of the way when not in use.

35 It is further noted that the angle plate used in connection with my improved locking device permits free operation of the upper sash without interference when the locking device is not in place.

40 It is evident also that we have provided an anti-rattler and locking device which may be made up at small cost and which can without much trouble be secured to a window sash frame and positioned relatively to the 45 sashes for efficient and effective use.

While we have illustrated and described our invention with some degree of particularity, we realize that in practice various alterations therein may be made. We therefore reserve the right and privilege of changing the form of the details of construction or otherwise altering the arrangement of the correlated parts without departing from the spirit of the invention or the scope of the appended claims.

Having thus described our invention what we claim as new and desire to secure by United States Letters Patent is:

1. A combination burglar-proof and anti-rattle device comprising a plate arranged to be secured at one side of the sash frame, a sash engaging strip hinged thereto and shaped to provide a shoulder for engagement with the upper edge of one of the sashes 65 whereby rattling and unauthorized opening

movement of the sash is prevented, and means for securing said strip to the plate in its sash engaging position.

2. A combination burglar-proof and anti-rattle device for windows comprising a plate 70 secured to the sash frame, a strip hinged thereto and having a shouldered edge for engagement with the edge of the sash to prevent rattling and raising thereof, a member secured to the other sash and cooperating 75 with said strip to prevent lowering of said sash, and means for securing the strip to the plate in said sash engaging position.

In testimony whereof we affix our signatures.
